ARTHUR H. KUHLMANN, OF UNIVERSITY CITY, MISSOURI

WEATHERPROOFING MEANS

Application filed February 4, 1929. Serial No. 337,290.

An object of the invention is to provide a metal parting bead, and improved means employed therewith, for weather proofing windows of metal or wood construction. An improvement and advantage of my device lies in the provision of means whereby an effective seal is formed between the sash and frame, even though there be considerable side or end play between these members.

10 Another object of my invention is to provide means to check side play in window sashes, and to eliminate the rattling noise caused by wind.

A further object of my invention is to provide a weather strip which permits the sash to be easily removed and replaced without distorting or removing any member of the strip, from its secured position in the window assembly.

20 A still further object and advantage is attained in the ease and facility with which the weather proofing of my invention can be installed, since it has been found that an ordinary mechanic is able to equip a window with my device in considerably less time than is required with any of the prevailing types.

Other objects and advantages will appear from the following detailed description of a single executional embodiment of my invention and the accompanying drawings thereof, in which Fig. 1 shows a horizontal sectional view through a portion of a window frame and upper and lower sashes, to which my parting member and weather strip has been applied; Fig. 2 is a perspective, phantom view, the purpose of which is to illustrate the position of the biasing member hereinafter described; Fig. 3, a fragmentary perspective view, shows a metal parting bead of prefered form, and paired weather proofing members in operable disposition; and Fig. 4 is a sectional elevation taken on line 4—4 of Fig. 1, and shows a preferred method of securing the parting bead into position.

45 Referring now to Fig. 1, upper and lower sashes 5 and 6 are adapted to slide vertically in their respective guideways formed by the pulley stile member 7, the outer bead 8, and the inner bead 9. The pulley stile 7, is provided with a groove or channel 10 which con-

stitutes a seat for a spacing member or parting bead. In the ordinary window construction, the parting bead is of standard width and usually comprises a strip of wood, rectangular in cross section, which runs from the bottom to the top frame members. 55

I prefer, however, to provide a parting bead 11, of sheet metal. Zinc or copper is well adapted for this purpose, although any non-rusting metal or rust-resisting metal may well be used. My parting bead comprises, essentially, a hollow rectangular member, one wall of which has a narrow, longitudinal opening 12, cut centrally therethrough. The parting bead is adapted to be positioned in the channel 10 with the slotted wall outermost, and preferably secured by means of angulate members such as 13, at the ends thereof. These members, fastened as by screws 14, into the top and bottom frame member, provide a simple expedient for holding the parting bead into the groove, and permit the bead to be easily and quickly removed. 70

75 My weather strip comprises, essentially, a sealing member 15, which cooperates, in slidable engagement with member 16, to form a seal in the manner illustrated in Fig. 3. The members 16, which for convenience will be termed slidable members, are fastened to the stiles of the sash, and preferably extend the full length of these members. A plan view of the sliding members reveals a straight portion 17, a bend 18, and curved portion 19. The portion 17 is provided with perforations 20 at suitable intervals along its length, and nails or screws, indicated at 21, extend through these apertures and serve to fasten the sliding members to the sash. The marginal portion is preferably rebent, as shown, thereby protecting the heads of the securing elements and producing a sliding surface of relatively small area. 80

85 The sealing member 15, preferably of channeled construction and formed also of sheet metal, includes a corrugated flange 22, a web 23, and a portion 24 which, by preference, is curved to conform with portion 19 of the sliding member 16. It is obvious that the mating portions 19 and 24 may be of any suitable form, but I prefer to make them arcuate, 90 100

and thus improve the seal formed therebetween. The corrugated flange 22 is adapted to be disposed within the parting bead and the web 23 extends through the opening 12, in the manner shown. A resilient member 25, preferably in the form of a semi-elliptical spring, is positioned between the front wall of the parting bead and the flange 22 and frictionally retained by means of the corrugations, and permits the sealing member to be moved outwardly of the parting bead, against the biasing action of the spring. By reason of the spring and semi-floating position of the sealing member, this latter element is constantly held in contact with the sliding member, and the seal is maintained in spite of sidewise movement or irregularities of the frame. In window constructions, a condition is often encountered where from wear or other reasons, the sash stiles are not parallel to the pulley stiles. It is therefore advisable to make provision to compensate for this misalignment by permitting, as in the present example, the members 15 to assume a variable angular position, through a range of a few degrees, with respect to the parting bead, which is usually secured in parallel relation to the pulley stiles. Otherwise expressed, the springs 25 are so disposed as to permit dissimilar distance relations to exist, along and between portions of the members 15 and the parting bead.

Although sealing members only slightly in excess of sash length would be sufficient, I prefer to extend these elements the full length of the window frame, and provide springs at suitable spacings along their length. By this arrangement, the weather proofing is effective regardless of the position of the sash, and all noise caused by the rattling of a loose sash is eliminated.

In installing the weather stripping of my invention, the members 16 are nailed or screwed to the stiles in the manner shown. The upper or outer sash 5 is put in the frame and retained by means of the parting bead. The parting bead, with sealing members and springs assembled therein, is placed in the groove 10, it being necessary to draw the member 15, outwardly against the action of the springs so as to permit engagement with the sliding member. In like manner, the lower or inside sash is positioned and secured by means of the inside bead 9.

It will thus be obvious to those skilled in the art, that my device affords many advantages over prevailing forms of weather stripping. Many of these employ a metal strip cooperating with a channel cut into the sash or frame and the cutting and fitting of the channel and strip member, demand a consideration amount of the time of a skilled mechanic.

While the above description and the accompanying drawings illustrate a preferred

embodiment of my device, I do not wish to limit it to the specific construction and arrangement of parts shown, as various modifications and deviations may be made without departing from the full spirit and scope of my invention. 70

I claim:

1. In a combined weather strip and parting bead, means forming a sealing structure movably associated with the parting bead and comprising a longitudinally disposed member, and an element movable along said member. 75

2. A weather strip including a hollow parting bead, and a sealing member having an angulate portion disposed, and resiliently positioned transversely of in the parting bead. 80

3. A weather strip including a hollow parting bead having a wall opening and a sealing member extending through said opening in floating relation to the parting bead and adapted for transverse movement relative to said parting bead. 85

4. A combined parting bead and weather stripping means, comprising a rectangular metal tube having a longitudinally disposed slotted wall opening, a sealing structure extending through the wall opening and into said tube, and means associating the tube and sealing structure for relative movement transversely of the tube. 90

5. In a weather-strip structure, a hollow parting bead having a slotted wall opening, a sealing member extending through the slot and into the parting bead, and means for associating said parting bead and sealing member in movable relation. 100

6. In a weather strip, a tubular parting bead, a sealing member extending therein, and a resilient member disposed between said parting bead and said sealing member. 105

7. In a weather strip, a tubular parting bead, a sealing member distinct from said parting bead, and resilient means, disposed within said parting bead and adapted to bias said sealing member. 110

8. In a combined weather strip and parting bead, a channeled member, a member longitudinally slid able with respect thereto, and having a portion adapted to cooperate with the channeled member, and resilient means, tending to maintain contact between said members. 115

9. In a structure including a weather strip and a tubular parting bead, a spring member, frictionally retained between portions of said weather strip and parting bead. 120

10. In a combined weather strip and parting bead, a sealing member having a corrugated portion adapted to position a spring biasing member, by frictional engagement therewith. 125

11. A weather strip including a tubular parting bead, a substantially channel-shaped sealing member disposed longitudinally in 130

the parting bead, and resilient means bearing against said parting bead and said sealing member.

12. A weather strip structure including a parting bead, a member adapted to be carried by a sash, and movable relative to the parting bead, means forming a weather seal with said movable member, and means for yieldingly positioning one of said sealing members relative to said parting bead.

13. A combined weather strip and parting bead structure including a beaded member adapted to be carried by a sash, a slideway for the beaded member, and means for yieldingly positioning said slideway relative to the window frame.

14. In a combined weather strip and parting bead structure, a hollow parting bead, sealing means extending into the parting bead, a member adapted to be carried by a sash, said means and member being arranged with portions in overlapping relation; and means for maintaining a running seal between said member and said sealing means.

15. In a combined parting bead and weather strip structure, a slideway carried by the parting bead and means permitting a variable angular relation between said slideway and the parting bead.

16. In a combined parting bead and weather strip structure, a slideway, a slide associated therewith, and combined means for maintaining contact between said slideway and slide, and for permitting dissimilar distance relations between different portions of the slideway and the parting bead.

17. A combined weather strip and parting bead structure adapted to be employed in lieu of a standard parting bead, and including a hollow, rectangular parting bead, formed of sheet metal and having a longitudinally slotted wall; a pair of oppositely disposed sealing members, of channeled construction extending through said slot, and each including a slideway of substantially arcuate section, exterior to said parting bead; a spring disposed within the parting bead and engaging a wall thereof, and one of said sealing members, and adapted to position, and to permit movement of, the associated sealing member, transversely to the parting bead; a member adapted to be carried by a sash, and including a sliding surface for engagement with said slideway, and means, including said spring, for maintaining a substantially uniform area of engagement between said sliding surface and said slideway, throughout their length.

ARTHUR H. KUHLMANN.
